CLAIM

The ornamental design for a toilet brush set, as shown and described.

DESCRIPTION

FIG. 1 is a front, right and top perspective view of a toilet brush set, showing my new design.

FIG. 2 is a front, left and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a front, right and top perspective view of the toilet brush set in use with the lid open.

The broken lines illustrate portions of the toilet brush set that form no part of the claimed design.

1 Claim, 9 Drawing Sheets
